(57) **CLAIM**

The ornamental design for a chair, as shown and described.

DESCRIPTION

FIG. 1 is a front elevational view of a chair showing my new design prior to its configuration for seating use;

FIG. 2 is a rear elevational view thereof, shown prior to its configuration for seating use;

FIG. 3 is a top plan view thereof, shown prior to its configuration for seating use;

FIG. 4 is a bottom plan view thereof, shown prior to its configuration for seating use;

FIG. 5 is a right side elevational view thereof, shown prior to its configuration for seating use;

FIG. 6 is a left side elevational view thereof, shown prior to its configuration for seating use;

FIG. 7 is a front and right side perspective thereof, shown prior to its configuration for seating use;

FIG. 8 is a front elevational view thereof, shown configured for seating use;

FIG. 9 is a rear elevational view thereof, shown configured for seating use;

FIG. 10 is a top plan view thereof, shown configured for seating use;

FIG. 11 is a bottom plan view thereof, shown configured for seating use;

FIG. 12 is an exploded left side elevational view thereof, shown in the process of configuration for seating use;

FIG. 13 is an exploded right side elevational view thereof, shown in the process of configuration for seating use;

FIG. 14 is a front and right side perspective view shown configured for seating use;

FIG. 15 is an exploded front and right side perspective view thereof, shown in the process of configuration for seating use;

FIG. 16 is a reduced front and right side perspective view thereof, shown prior to its configuration for seating use;

FIG. 17 is a reduced front and right side perspective view thereof, shown in the process of configuration for seating use;

FIG. 18 is a reduced front and right side perspective view thereof, shown in the process of configuration for seating use; and,

FIG. 19 is a reduced front and right side perspective view thereof, shown configured for seating use. The cord element in the views is shown broken-away to indicate unclaimed length.
